FLOODLIGHT

Eldon L. Anderson, Jr., Fletcher, N.C., assignor to
General Electric Company

Filed Sept. 17, 1971, Ser. No. 181,657

Term of patent 14 years

Int. Cl. D26—03

U.S. Cl. D48—20 K

FIG. 1 is a perspective view of a floodlight embodying my new design;

FIG. 2 is a side elevational view thereof; and

FIG. 3 is a rear elevational view thereof.

I claim:

The ornamental design for a floodlight, as shown.
